UNITED STATES PATENT OFFICE.

HARRY L. RICE, OF QUINCY, MASSACHUSETTS, ASSIGNOR TO THE RICE & HUTCHINS, INCORPORATED, OF BOSTON, MASSACHUSETTS.

DESIGN FOR A HEEL AND SOLE PROTECTOR.

SPECIFICATION forming part of Design No. 34,183, dated March 5, 1901.

Application filed January 28, 1901, Serial No. 45,152. Term of patent 14 years.

To all whom it may concern:

Be it known that I, HARRY L. RICE, a citizen of the United States, residing at Quincy, in the county of Norfolk and State of Massachusetts, have invented and produced a new and original Design for a Heel and Sole Protector, of which the following is a specification, reference being had to the accompanying drawings, forming a part thereof.

Figure 1 is a perspective view of a heel and sole protector, showing my new design. Fig. 2 is a plan view of the same.

The leading feature of my design for a heel and sole protector consists of a body comprising two portions *a* *b*, connected by a short transverse portion *c*, the portion *a* having connected with it at the top an outwardly-

extending looped or doubled portion *d*, from which projects downwardly and outwardly a slightly-curved portion *e*, the said several portions being made tapering or wedge-shaped from their upper to their lower edges, as shown.

Having described my invention, what I claim as new, and desire to secure by Letters Patent, is—

The design for a heel and sole protector, substantially as herein shown and described.

In testimony whereof I have signed my name to this specification in the presence of two subscribing witnesses.

HARRY L. RICE.
